UNITED STATES PATENT OFFICE.

JOSEPH HUNTER DICKINSON, OF LARCHMONT, NEW YORK, ASSIGNOR TO THE
AEOLIAN COMPANY, A CORPORATION OF CONNECTICUT.

MULTIPLE-RECORD-MAGAZINE PHONOGRAPH.

Application filed April 5, 1917. Serial No. 159,918.

To all whom it may concern:

Be it known that I, JOSEPH HUNTER DICKINSON, a citizen of the United States of America, and a resident of Larchmont, 5 Westchester county, and State of New York, have invented certain new and useful Improvements in Multiple-Record-Magazine Phonographs, of which the following is a specification, reference being had to the accompanying drawings, forming a part thereof.

My invention relates to improvements in multiple record magazine phonographs and its object is to provide an automatic mechanism for consecutively playing a plurality of records. More specifically, its object is to provide a simple and efficient automatic apparatus for removing the upper one of several superimposed disc records after it 20 has been played and at the same time moving the reproducer back into position to engage the first part of the next adjacent record.

In order that my invention may be thoroughly understood, I will now proceed to describe the same in the following specification, and then point out the novel features thereof in appended claims.

Referring to the drawings:

Figure 1 is a top plan view partly in section, of an instrument made according to and embodying my invention.

Figure 2 is a side elevation partly in section, of the same apparatus.

Figure 3 is a central sectional front elevation of my improved mechanism, the section being taken on the line 3—3 of Figure 1.

Figure 4 is a sectional front elevation of a part of the same mechanism, the section in this figure being taken on the line 4—4 of Figure 1.

Figure 5 shows one of the parts in front elevation, this part being a pair of shiftable gears, the use of which will be fully described.

Figure 6 is a sectional elevation of certain of the parts and illustrates a detail of construction.

Figure 7 is a plan view of some of the parts shown in Figure 6, the view being taken on the line 7—7 of the latter figure.

Figure 8 is a side elevation of a part of the device, this figure showing in detail a lock actuating mechanism.

Figure 9 is a diagram showing certain of the parts in elevation, and plan, and also showing their interconnecting electrical circuits.

Figure 10 is a plan view of the adjustable contact devices shown in Figures 1 and 2.

Figure 11 is a front elevation of the device shown in Figure 9.

Figure 12 is a side elevation of some of the parts shown in Figure 10, the view being taken from the line 12—12 of the latter figure.

Like characters of reference designate corresponding parts in all the figures.

10 designates a part of the case or frame of the instrument, 11 its reproducer, 12 its tone arm which is pivotally connected at 13 with a bend 14, which is swiveled at 15 and connected with the upper end of the amplifying horn 16.

17 is the horizontal table of the instrument and 18 is an inclined shelf at one side thereof.

Under the table is a plate 20 upon which certain parts of the apparatus are supported. 21 is the turn-table shaft, the lower end of which is supported by a bracket 22 depending integrally from the plate 20. A worm gear 23 on this shaft meshes with a worm 24 on a shaft driven by some suitable motor connected with a pulley 25 on the same shaft. The governor 26 is also on this shaft and carries a disc 27 which is arranged to coact with a manually adjustable brake shoe 28 in the usual manner. The upper end of the shaft forms a spindle 29 which extends freely through all but the upper one of a plurality of superimposed records 19.

30 is a vertically slidable sleeve mounted in a bearing 31 formed as a part of the plate 20 and supported upon the bifurcated end of a lever 32 which is affixed to a horizontal shaft 33 mounted in suitable bearings 34 under plate 20. 35 is another lever affixed to shaft 33 to the lower end of which is attached a spring 36 which passes through an angle bracket 37 affixed to plate 20. 38 is an adjusting member for the spring 36 by means of which its tension may be regulated.

The turn-table 40 fits over the spindle 29 and is keyed to turn with the shaft but is at the same time free to move up vertically.

thereon. The turn-table is supported on a disc 41 on the upper end of the sleeve 30; a disc 42 being under the turn-table and separated from the disc 41 by ball bearings 43.

5 It is desirable, as will appear later, to lock the sleeve 30 against its vertical movement during certain parts of the operation, and for this purpose I provide a screw 50 which passes through and engages threads in the 10 upper part of bearing 31. A lever 51 is adjustably secured to this screw. A pin 52 near the lower end of this lever is in a slot 53 in the end of a connecting rod 54, and a spring 55 affixed to lever 51 and to connecting rod 54 at 56 has a tendency to seat pin 52 in the bottom of slot 53 and to turn the lock screw 50 in the direction to lock.

At one corner of the plate 20 is a member 60 which forms bearings for a vertical post 20 61 capable of a rotary oscillation. 62 is a collar affixed to this post to hold it from moving downwardly. A lever 63 is affixed to its lower end. 64 is a bracket depending from plate 20 to support an adjustable stop screw 65 by means of which the inward movement of the lever 63 is limited. 66 is a spring which is arranged to oppose the outward movement of the lever 63 and the parts which are connected therewith, and has a 25 tendency to hold the lever 63 against the stop screw 65.

30 70 is an arm which is removably connected to the upper end of post 60. It has a vertical hub 71 through which a screw 72 passes into the post 61. The lower end of this hub is made with a transverse slot which fits over a rib 67 on the upper end of the post so that the arm 70 will swing with the oscillations of the post. The free end of 35 40 arm 70 is constructed to form a head 73 in which is a rotatably supported member 74 having a central lug 75 which, when the arm is in its inner position, determined by the adjustment of the stop screw 65, is in alignment with the spindle 29 and extends into the center hole of the upper record 19. The lug 75 and the spindle 29 are separated from each other at the plane between the upper 45 two records 19. The lower end of the rotatable member is in the form of a small horizontal disc 76 from the center of which the lug 75 extends downwardly. This disc and the head 73 limit the upward movement of the records when they are raised by the 50 55 spring 36.

On the motor driven turn-table shaft 21 is a gear 80 which is in mesh with a larger gear 81 which is affixed to a vertical shaft 82. 83 is another gear on another shaft 84 60 on the lower end of which is a crank arm 85. This is connected by a rod 86 with lever 63 so that the rotation of gear 83 causes the post 61 to be oscillated and arm 70 to be 65 swung outwardly and back again. A slot and pin connection between crank 85 and

rod 86 provides a certain amount of lost motion and allows spring 66 to hold lever 63 against stop screw 65 during a part of the movement of the crank 85 over its dead center.

70 The gear 83 is spaced from and is higher than gear 81. Between them is a rock shaft 87. This carries a vertical transverse shaft to which are affixed a pinion 88 adapted to mesh with gear 81 and a pinion 89 adapted to mesh with gear 83. 90 is an arm extending from the rock shaft 87 and connected at its outer end with the core of a solenoid 91. 92 is a spring which raises this core and holds the pinions 88-89 out of engagement with their respective gears. When, however, the solenoid is energized, the arm 90 is pulled down and the shaft rocked to bring the pinions 88 and 89 into mesh with the gears 81 and 83 respectively, so that the motor driven gear 81 will, through this mechanism, drive gear 83 to swing the arm 70 outwardly and back again. As will be shown later, the circuit through solenoid 91 is broken automatically at the desired time to release the gears 88 and 89 and allow the spring 66 to hold lever 63 against stop screw 65 and to thus hold the lug 75 in alignment with spindle 29.

80 85 At the other end of the rock shaft 87 is an arm 93 to which the lock actuating rod 54 is connected so that when the rock shaft 87 is actuated the lock screw 50 will be turned. This results in locking the sleeve 30 against vertical movement during the time the arm 70 is oscillating.

- position of which is manually adjustable by means of a button above table 17. This is closed by engagement of the arm 100 with it as this arm is moved inwardly by the record 5 groove. When this circuit closer is closed a current passes from a battery or other source 111, through conductors 112 and 113 to and through solenoid 104 and back to the battery through conductor 115.
- 10 As soon as the solenoid 104 is energized a spring contact 116 which carries an armature 117 is raised against an adjustable stationary contact 118. The spring contact 116 is connected by a wire 119 with a circuit 15 breaker 120 which, by wire 121, is connected with the battery 111. The stationary contact 118 is connected by wire 122 with wire 113 which leads to the solenoid 104. This results in the solenoid remaining energized 20 even after the circuit closer 110 is opened as long as circuit breaker 120 remains closed.
- The circuit breaker 120 will remain closed until arm 100 in its outward movement strikes it which will be at a time predetermined by the position of the circuit breaker 120. The position of this circuit breaker is adjusted manually by a button on the upper side of table 17 as will be described later.
- 30 110^A is another circuit closer which closes a circuit from the battery 111 through wires 112, 123 and 124 to and through solenoid 91, which circuit is completed through wires 125 and 115.
- 35 When solenoid 91 is energized it draws up a spring contact 126 against an adjustable stationary contact 127. The wire 112 from the battery 111 is connected to the spindle of gear 83 by wire 128 and a spring contact 129. Another spring contact 130 bears on the upper surface of this gear in certain of its positions. 131 is a wire from spring contact 130 to spring contact 126, and 132 is a wire from stationary contact 127 to the wire leading into the solenoid 91 so that through these parts the circuit is maintained through the solenoid 91 to keep the gears which it controls in operation until the arm 70 has been swung over with a record to its outer position and back again. A block of insulation 133 is set into gear 83 and at the proper time spring contact 130 runs onto this insulation, thus breaking the circuit through solenoid 91 and allowing spring 50 92 to move the pinions away from gears 81 and 83. The spring 66 will now hold the arm 70 to its inner position with its lug 75 in alignment with the spindle 29.
- I will now describe the means for adjusting the positions of the circuit closers 110 and 110^A and of the circuit breaker 120. Referring to Figures 1, 2, 10, 11 and 12, 140 is a plate spaced from the under side of table 17 and supported thereby. To this 60 is secured a flat support 141. 142 is a pivot which rotatively supports an arm 143, the inner end of which is in the form of a flat sector 144. The outer end of arm 143 is bent upward as at 145 and supports a block of insulation 146 on which is supported a 70 pair of light springs 147 and 148. 149 is a contact electrically connected with the vertical part of arm 143. 150 is a contact on the spring 147 and 151 a similar contact on spring 148. The springs 147 and 148 have 75 a tendency to hold the contacts 150 and 151 away from contact 149 a distance determined by the ends 152 and 153 of the springs which are bent over as shown and arranged to abut against the back of the insulation 80 block 146.
- 154 is a spring around pivot 142 and connected thereto and to arm 143 at 155 and so arranged as to have a tendency to swing arm 143 in an anti-clockwise direction as 85 viewed in Figure 1.
- 156 is a brake rod pivoted in bearings 157 on the plate 140. Its inner end is bent at right angles to form a brake finger 158 which is pressed against sector 144 by a 90 comparatively strong spring 159 to hold the arm 143 against the action of spring 154. The other end 160 of rod 156 is bent at right angles in the opposite direction to the finger 158 and to the outer end thereof 95 which is pivotally connected a vertical rod 161 which passes up through table 17 and terminates in a button 162.
- The manner of setting this device is as follows: The tone arm 12 is moved to such 100 a position that the reproducer needle is at the end of the playing part of the record and arm 100 is moved with the tone arm and positioned thereby. At this time the button 162 is depressed to move brake finger 158 off of sector 144. The spring 154 will press springs 147 and 148 against the arm 100 with sufficient pressure to cause their contacts 150 and 151 to be moved against contact 149. Now button 162 is 105 released and brake finger 158 pressing against sector 144 will lock the arm 143 in the position which it has assumed.
- When the instrument is played, and the tone arm moved by the reproducer needle 115 following the pitch of the spiral record groove until it has reached the position at which the parts have been set as described, the arm 100 will again close contacts 150 and 151 against contact 149 at the desired 120 time. Contacts 150 and 149 form circuit closer 110, and contacts 151 and 149 form circuit closer 110^A. Thus when the reproducer needle reaches the end of the record, the solenoids 91 and 104 will be energized to 125 perform their functions.
- 163 is another swinging arm supported on a pivot 164 on base 141. This is actuated by a spring 165 in a clockwise direction when released by pressing a but- 130

ton 166 downwardly. 167 is a block of insulation on the outer end of arm 163. A light spring 168 carried by this block has on its bent-over end 169 a contact 170 which is held by this spring against a contact 171 which is electrically connected with the arm 163. The position of this arm is similarly set when the reproducer needle is at the beginning of a record. Contacts 170 and 171 form the circuit breaker 120 and are separated to deenergize solenoid 104 at the desired time.

The operation of the device may be seen from the foregoing description, but to make it clearer, I will describe it as a whole. A desired number of records are placed upon the turn-table 40 and the circuit closers 110 and 110^A set in desired position as is also the circuit breaker 120. The arm 70 is placed with its head 73 over the center of the records. The spring 36 will raise the turn-table 40 until the upper record is in contact with disc 76 which thereby limits the upward movement of the turn-table. The instrument may now be played in the usual manner, when the reproducer needle reaches the end of the upper record, circuit closers 110 and 110^A will be closed in the manner which has been described and solenoids 104 and 91 energized.

I have shown that the energization of solenoid 104 caused the tone arm to be raised, brought back to the beginning of the records and lowered thereon. Also that at the same time the energization of solenoid 91 operates lock screw 50 and causes arm 70 to be swung outwardly and back again. During this movement of arm 70 its lug 75 engaging the upper record will cause the latter to be slid off from the other records, the position of which will be maintained by spindle 29.

When arm 70 has reached its outer position, the record which it has carried with it, will drop and slide by gravity down the incline 18. As soon as arm 70 reaches its inner position and its alignment with spindle 29 maintained by spring 66 and stop screw 65, the spring contact 130 will run onto insulation 133 to thereby break the circuit through solenoid 91. This then allows spring 92 to move rock shaft 87 to disengage gears 88 and 89 from gears 81 and 83 and to release lock screw 50. The rotation of gear 83 will stop and the spring 36 will then raise the turn-table 40. This occurs before the tone arm has been wholly retracted, so that when the latter has moved out until arm 100 causes circuit breaker 120 to open the circuit through solenoid 104 to lower the reproducer needle, the latter will come on a new record. This operation will be repeated.

When it is desired to use this instrument

with a single record, it is only necessary 65 to remove the screw 72 and the arm 70.

Many structural modifications may be made within the spirit and scope of this invention, and I intend no limitations other than those imposed by the appended claims. 70

What I claim is:

1. In a phonograph, a rotary spindle, a record holding turn-table thereon, an arm arranged to oscillate in a plane parallel with said turn-table having a lug adapted 75 in one position of the arm to be in alignment with said spindle, and to engage a record on the turn-table, and means for moving said arm across the turn-table to thereby remove the engaged record therefrom. 80

2. In a phonograph, a rotary spindle, a record holding turn-table thereon, an oscillatory arm having a lug adapted in one position of the arm to be in alignment with 85 said spindle and to engage a record on the turn-table, means for moving said arm across the turn-table to thereby remove the engaged record therefrom, and means for raising the turn-table toward said lug. 90

3. In a phonograph, a rotary spindle, a record holding turn-table thereon, an oscillatory arm having a lug adapted in the inner position of the arm to be in alignment with said spindle and to engage a 95 record on the turn-table, means for moving said arm in a plane parallel with the turn-table to thereby remove the engaged record therefrom, means for raising the turn-table toward said lug, and a lock for preventing 100 the upward movement of the turn-table except when the arm is in its inner position. 105

4. In a phonograph, a vertical rotary spindle, a record holding turn-table thereon, an oscillatory arm having a head at the end thereof and a lug projecting from said head, adapted in one position of the arm to be in alignment with said spindle and to engage a record on the turn-table, means for moving said arm in a plane parallel with 110 the turn-table to thereby remove the engaged record therefrom, and means for pushing said turn-table upward, and means carried by said head for limiting the upward movement of the turn-table by engagement 115 with a record thereon.

5. In a phonograph, a vertical rotary spindle, a record holding turn-table thereon, an oscillatory arm having a head at the end thereof, a rotative member supported 120 by said head having a lug projecting therefrom adapted in one position of the arm to be in alignment with said spindle and to engage a record on the turn-table, means for moving said arm in a plane parallel with the turn-table to thereby remove the engaged record therefrom, and an adjustable 125 spring arranged to push said turn-table up-

- ward, said rotative member being arranged to limit the upward movement of the turn-table by engagement with a record thereon.
6. In a phonograph, a rotary spindle, 5 means for driving the spindle, a record holding turn-table mounted on the spindle, a movable tone arm, means for sliding a record off from the turn-table, and means driven from said spindle and controlled by 10 the movement of the tone arm for actuating said record sliding means.
7. In a phonograph, a rotary spindle, means for driving the spindle, a record holding turn-table mounted on the spindle, 15 a movable tone arm, an oscillatory arm pivotally supported outside of the turn-table, said arm having a lug projecting downwardly adapted in the inner position of the arm to be in alignment with the spindle and to engage a record on the turn-table, 20 and means driven from said spindle and controlled by the movement of the tone arm for swinging said arm in a plane parallel with the turn-table to thereby remove the 25 engaged record therefrom.
8. In a phonograph, a vertical rotary spindle, means for driving the spindle, a record holding turn-table slidably but non-rotatively mounted on the spindle, a movable tone arm, an oscillatory arm pivotally supported outside of the turn-table, said arm having a head at its free end, a rotative member supported by said head having a lug projecting downwardly therefrom 30 adapted in the inner position of the arm to be in alignment with the spindle and to engage a record on the turn-table, means driven from said spindle and controlled by the movement of the tone arm for swinging 35 said arm in a plane parallel with the turn-table to thereby remove the engaged record therefrom, and means for pushing said turn-table upward, said member being arranged to limit the upward movement of 40 the turn-table by engagement with a record 45 thereon.
9. In a phonograph, a vertical rotary spindle, means for driving the spindle, a record holding turn-table mounted on the 50 spindle, a movable tone arm, an oscillatory arm pivotally supported outside of the turn-table, said arm having a lug projecting downwardly adapted in the inner position of the arm to be in alignment with the 55 spindle and to engage a record on the turn-table, shiftable gearing for connecting the oscillatory arm with the spindle for swinging said arm in a plane parallel with the turn-table to thereby remove the engaged record 60 therefrom, and means controlled by the movement of the tone arm for shifting said gearing into connecting positions.
10. In a phonograph, a vertical rotary spindle, means for driving the spindle, a 65 record holding turn-table mounted on the spindle, a movable tone arm, an oscillatory arm pivotally supported outside of the turn-table, said arm having a lug projecting downwardly adapted in the inner position of the arm to be in alignment with the spindle and to engage a record on the turn-table, shiftable gearing for connecting the oscillatory arm with the spindle for swinging said arm to thereby remove the engaged record 70 therefrom, electro-magnetic means for shifting said gearing into connecting position, an electric circuit therefor, and a circuit closer actuated by the movement of the tone arm.
11. In a phonograph, a vertical rotary spindle, means for driving the spindle, a record holding turn-table mounted on the spindle, a movable tone arm, an oscillatory arm pivotally supported outside of the turn-table, said arm having a head at its free end, a rotative member supported by said head having a lug projecting downwardly adapted in the inner position of the arm to be in alignment with the spindle and to engage a record on the turn-table, shiftable 80 gearing for connecting the oscillatory arm with the spindle for swinging said arm in a plane parallel with the turn-table to thereby remove the engaged record therefrom, electro-magnetic means for shifting said 85 gearing into connecting position, an electric circuit therefor, and a circuit closer actuated by the movement of the tone arm.
12. In a phonograph, a vertical rotary spindle, means for driving the spindle, a record holding turn-table mounted on the spindle, a movable tone arm, an oscillatory arm pivotally supported outside of the turn-table, said arm having a lug projecting downwardly adapted in the inner position 90 of the arm to be in alignment with the spindle and to engage a record on the turn-table said arm being arranged to be swung in a plane parallel with said turn-table to thereby remove the engaged record therefrom, 95 a vertical shaft, connections between the vertical shaft and the oscillatory arm, a gear on the spindle, another gear on the vertical shaft offset vertically from said spindle gear, a rock shaft between said gears, 100 a pair of pinions swingingly supported by the rock shaft and arranged to be moved into and out of engagement with said gears by the movement of the rock shaft, and means controlled by the movement of the 105 tone arm for moving the rock shaft.
13. In a phonograph, a vertical rotary spindle, means for driving the spindle, a record holding turn-table mounted on the spindle, a movable tone arm, an oscillatory 110 arm pivotally supported outside of the turn-table, said arm having a lug projecting downwardly adapted in the inner position of the arm to be in alignment with the spindle and to engage a record on the turn-table, shiftable gearing for connecting the oscillatory arm with the spindle for swinging said arm in a plane parallel with the turn-table to thereby remove the engaged record therefrom, electro-magnetic means for shifting said gearing into connecting position, an electric circuit therefor, and a circuit closer actuated by the movement of the tone arm.

of the arm to be in alignment with the spindle and to engage a record on the turn-table, said arm being arranged to be swung in a plane parallel with said turn-table to thereby remove the engaged record therefrom, a vertical shaft, connections between the vertical shaft and the oscillatory arm, a gear on the spindle, another gear on the vertical shaft offset vertically from said 5 spindle gear, a rock shaft between said gears, a pair of pinions swingingly supported by the rock shaft and arranged to be moved into and out of engagement with said gears by the movement of the rock 10 shaft, electro-magnetic means for moving the rock shaft, an electric circuit therefor, and a circuit closer actuated by the movement of the tone arm.

14. In a phonograph, a vertical rotary 20 spindle, means for driving the spindle, a record holding turn-table mounted on the spindle, a movable tone arm, having a member rigidly affixed thereto, an oscillatory arm pivotally supported outside of the turn-table, said arm having a lug projecting downwardly adapted in the inner position of the arm to be in alignment with the spindle and to engage a record on the turn-table, said arm being arranged to be swung 25 in a plane parallel with said turn-table, to thereby remove the engaged record therefrom, a vertical shaft, connections between the vertical shaft and the oscillatory arm, a gear on the spindle, another gear on the 30 vertical shaft offset vertically from said spindle gear, a rock shaft between said gears, a pair of pinions swingingly supported by the rock shaft and arranged to be moved into and out of engagement with said 35 gears by the movement of the rock shaft, a solenoid having a core connected with and adapted to move the rock shaft, an electric circuit therefor, a movable circuit closer in said circuit, and manual means for adjusting the position of the circuit closer in the 40 path of movement of the tone arm member.

15. In a phonograph, a rotary spindle, means for turning the spindle, a record holding turn-table mounted on the spindle, a 50 movable tone arm, an oscillatory arm having a lug projecting downwardly adapted in the inner position of the arm to be in alignment with the spindle and to engage a record on the turn-table, a spring arranged 55 to hold said arm in its inner position, means driven from said spindle and controlled by the movement of the tone arm for moving said arm in a plane parallel with the turn-table against the action of 60 said spring, to thereby remove the engaged record therefrom.

16. In a phonograph, a rotary spindle, means for driving the spindle, a record holding turn-table mounted on the spindle, 65 a movable tone arm, an oscillatory arm

having a lug projecting downwardly adapted in the inner position of the arm to be in alignment with the spindle and to engage a record on the turn-table, a spring arranged to hold said arm in its inner position, shiftable gearing for connecting the oscillatory arm with the spindle for moving said arm in a plane parallel with the turn-table against the action of said spring to thereby remove the engaged record therefrom, means controlled by the movement of the tone arm for shifting said gearing into connecting positions, and means controlled by the movement of the oscillatory arm for shifting said gearing out of connecting positions. 70 75 80

17. In a phonograph, a rotary spindle, means for driving the spindle, a record holding turn-table mounted on the spindle, a movable tone arm, an oscillatory arm pivotally supported outside of the turn-table, said arm having a lug projecting downwardly adapted in the inner position of the arm to be in alignment with the spindle and to engage a record on the turn-table, a spring adapted to hold said arm in its inner position, shiftable gearing for connecting the oscillatory arm with the spindle for swinging said arm in a plane parallel with the turn-table to thereby remove the engaged 90 record therefrom, electro-magnetic means for shifting said gearing into connecting position, an electric circuit therefor, a circuit closer actuated by the movement of the tone arm, and a circuit breaker actuated by 95 the movement of said gearing. 100

18. In a phonograph, a vertical rotary spindle, means for driving the spindle, a record holding turn-table mounted on the spindle, a movable tone arm, a member rigidly affixed thereto, an oscillatory arm pivotally supported outside of the turn-table, said arm having a lug projecting downwardly adapted in the inner position of the arm to be in alignment with the spindle and to engage a record on the turn-table, a spring adapted to hold said oscillatory arm in its inner position, said arm being arranged to be swung in a plane parallel with said turn-table, to thereby remove the engaged 105 record therefrom, a vertical shaft, connections between the vertical shaft and the oscillatory arm, a gear on the spindle, another gear on the vertical shaft offset vertically from said spindle gear, a rock shaft between said gears, a pair of pinions swingingly supported by the rock shaft and arranged to be moved into and out of engagement with said gears by the movement of the rock 110 shaft, a solenoid having a core connected with and adapted to move the rock shaft, an electric circuit therefor, a movable circuit closer in said circuit, manual means for adjusting the position of the circuit closer in the path of movement of the tone arm, and a circuit breaker actuated by 115 the movement of said gearing. 120 125 130

arm member, and a circuit breaker on one of said gears arranged to break the circuit to the solenoid at a predetermined point in the movement of the oscillatory arm.

5 19. In a phonograph, a rotary spindle, means for driving the spindle, a record holding turn-table mounted on the spindle, a tone arm arranged to be moved in one direction to follow the radial pitch of a spiral 10 record groove, an oscillatory arm having a lug projecting downwardly adapted in the inner position of the oscillatory arm to be in alignment with the spindle and to engage a record on the turn-table, means driven 15 from the spindle for moving the tone arm in the opposite direction, other means driven from the spindle for moving the oscillatory arm across the turn-table to thereby remove the engaged record therefrom, and means actuated by the first aforesaid movement of the tone arm for controlling both of said spindle driven means.

20. In a phonograph, a rotary spindle, means for driving the spindle, a record holding turn-table slidably but non-rotatively mounted on the spindle, a tone arm arranged to be moved in one direction to follow the radial pitch of a spiral record groove, an oscillatory arm having a head at its free end, 30 a rotative member supported by said head having a lug projecting downwardly therefrom adapted in the inner position of the arm to be in alignment with the spindle and to engage a record on the turn-table, means driven 35 from said spindle for raising the tone arm and moving said tone arm in the opposite direction, other means driven from the spindle for moving said oscillatory arm across the turn-table to thereby remove the engaged record therefrom, means for pushing 40 said turn-table upward, said member being arranged to limit the upward movement of the turn-table by the engagement with a record thereon, and means actuated by the first aforesaid movement of the tone arm for controlling both of said spindle driven means.

21. In a phonograph, a vertical rotary spindle, means for driving the spindle, a record holding turn-table mounted on the spindle, a tone arm arranged to be moved in one direction to follow the radial pitch of a spiral record groove, an oscillatory arm pivotally supported outside of the turn-table, said arm having a lug projecting downwardly adapted in the inner position of the arm to be in alignment with the spindle and to engage a record on the turn-table, shiftable gearing for connecting the oscillatory arm with the spindle for swinging said arm in a plane parallel with the turn-table to thereby remove the engaged record therefrom, means for raising the tone arm and moving said tone arm in the opposite direction, electro-magnetic means for shifting 60

said gearing into connecting position and for actuating said raising and moving tone arm means, and a circuit closer actuated by the movement of the tone arm.

22. In a phonograph, a rotary spindle, 70 means for turning the spindle, a record holding turn-table mounted on the spindle, a tone arm arranged to be moved in one direction to follow the radial pitch of a spiral record groove, an oscillatory arm having a lug projecting downwardly adapted in the inner position of the arm to be in alignment with the spindle and to engage a record on the turn-table, a spring arranged to hold 75 said arm in its inner position, means driven from said spindle and controlled by the movement of the tone arm for moving the tone arm in the opposite direction, and other means driven from said spindle and controlled by the movement of the tone arm for moving said oscillatory arm across the turn-table against the action of said spring, to thereby remove the engaged record therefrom, and means actuated by the first aforesaid movement of the tone arm for controlling 80 both of said spindle-driven means.

23. In a phonograph, a vertical rotary spindle, means for driving the spindle, a record holding turn-table mounted on the spindle, a tone arm arranged to be actuated in one direction to follow the radial pitch of a spiral record groove, a member rigidly affixed to said tone arm, an oscillatory arm pivotally supported outside of the turn-table, said arm having a lug projecting downwardly adapted in the inner position of the tone arm to be in alignment with the spindle and to engage a record on the turn-table, a spring adapted to hold said oscillatory arm in its inner position, said arm being arranged to be swung in a plane parallel with said turn-table, to thereby remove the engaged record therefrom, a vertical shaft, connections between the vertical shaft and the oscillatory arm, a gear on the spindle, another gear on the vertical shaft offset vertically from said spindle gear, a rock shaft between said gears, a pair of pinions swingingly supported on the rock shaft and arranged to be moved into and out of engagement with said gears by the movement of the rock shaft, a solenoid having a core connected with and adapted to move the rock shaft, an electric circuit therefor, a movable circuit closer in said circuit, manual means for adjusting the position of the circuit closer in the path of movement of the tone arm member, a circuit breaker on one of said gears arranged to break the circuit to the solenoid at a predetermined point in the movement of the oscillatory arm, combined with other means driven from said spindle for raising the tone arm and moving said tone arm in the opposite direction, and electromagnetic means for controlling 100

trolling said raising and moving means for the tone arm.

24. In a phonograph, a rotary spindle, a turn-table thereon adapted to hold a plurality of disc records, an oscillatory arm having a lug adapted in one position of the arm to be in alignment with said spindle but separated therefrom in the plane between the upper two records on the turn-table, and means for moving said arm across the turn-table to thereby remove the upper record therefrom.

25. In a phonograph, a rotary spindle, a turn-table adapted to hold a plurality of disc records, an oscillatory arm, a freely rotative member supported by said arm, said member having a part adapted to contact

with the surface of the uppermost record on the turn table and a lug depending from said part into said uppermost record, said lug being adapted in one position of the arm to be in alignment with said spindle but separated therefrom in the plane between the upper two records thereon, means for raising the turn-table to bring the surface of the uppermost record thereon into contact with the aforesaid part of the rotative member, and means for moving said arm across the turn-table to thereby remove said uppermost record therefrom. 20 25 30

In witness whereof, I have hereunto set my hand this 4th day of April, 1917.

JOSEPH HUNTER DICKINSON.
